UNITED STATES PATENT OFFICE

OTIS D. RICE, OF WINTHROP, MASSACHUSETTS

CONTINUOUS MECHANICAL DRIER

Application filed April 10, 1924. Serial No. 705,662.

This invention relates to a continuous mechanical drier for extracting moisture from material and it has for its general object to provide a drier of this class which comprises a series of continuously moving platen surfaces between which the material to be dried passes and which operates first to form said material into a thin strip or ribbon and then to subject the strip to progressively-increasing pressure thereby to express the liquid therefrom.

The device herein illustrated which embodies my invention comprises an endless trough conveyer into which the material to be dried is fed and an endless pressing unit or member co-operating with the trough conveyer to feed the material through the machine and to subject it to a progressively-increasing pressure as it passes through the machine, the pressure at the delivery end being gaged to remove the desired proportion of the liquid from the material.

Another feature of the invention relates to a construction which will prevent any of the liquid which has been forced out of the material from re-entering the dried material, this end being accomplished by employing such a construction that the liquid is drained away from the material as fast as it is squeezed out of it.

Another feature of the invention relates to a mechanical drier of this type in which one of the compression members, between which the material in sheet or ribbon form is compressed is in the form of a trough conveyer, and in which the material to be dried is fed to the conveyer by an endless feed unit which operates to initially compress the material and thus extract part of the liquid therefrom.

Another feature of the invention relates to a novel means for regulating both the pressure to which the sheet is subjected and the thickness to which said sheet is reduced at the delivery end of the machine.

Other objects of the invention are to improve generally mechanical driers in various ways all as will be more fully hereinafter set forth.

In order to give an understanding of the

invention I have illustrated in the drawings a selected embodiment thereof which will now be described after which the novel features will be pointed out in the appended claims.

In the drawings:

Fig. 1 is a side view of a mechanical drier embodying my invention;

Fig. 2 is a fragmentary sectional view through the active portions of the main compressing unit and conveyer;

Fig. 3 is an enlarged section on substantially the line 3—3, Fig. 1.

Fig. 4 is a fragmentary plan view showing the variable speed gear for driving the chain feed element;

Fig. 5 is an enlarged sectional view showing the slats with undercut edges.

The apparatus herein shown comprises a trough conveyer on which the material to be dried is carried through the machine, an endless chain feed element which aids in feeding the material to the conveyer and by which it is formed into a sheet or ribbon and initially compressed thereby expressing part of the liquid therefrom, and an endless chain main compressing element which co-operates with the trough conveyor to subject the material in ribbon form to the necessary pressure to express the liquid therefrom and to further reduce its thickness.

The device is also so constructed that the liquid which is expressed from the material will drain away from the material thus obviating the possibility of any of the expressed water re-entering the dried material.

Furthermore the device is constructed so that the pressure to which the material is subjected at the delivery end may be regulated and said material in ribbon form may be squeezed down to a predetermined thickness.

The trough conveyor is indicated generally at 1 and it is in the form of an endless conveyor which passes around sprockets 2 and 3 fast on shafts 80 and 81 that are suitably journaled in a frame 4. This trough conveyor may be of any suitable construction and is herein shown as comprising a plurality of slats or platens 5 that are linked together to form the endless conveyor, each slat having an end piece 6 extending from each end there-

of. These slats and end pieces thus form an endless trough conveyor.

This conveyor is positively driven by some suitable means, that herein shown being a motor 7 although so far as the invention is concerned any driving power may be employed for operating the conveyor. The motor is connected to the shaft 81 by a suitable reduction gear drive, that herein shown comprising a shaft extension 14 connected to the motor shaft and geared to a shaft 9 through suitable worm gearing 15, said shaft 9 having thereon a small sprocket wheel 16 which is connected by a sprocket chain 8 to a larger sprocket wheel 10. The sprocket wheel 10 is rigid with it a small sprocket wheel 11 which is connected by a sprocket chain 12 to a sprocket wheel 13 fast on the shaft 81. The above is simply illustrative of a speed-reducing drive which may be employed.

20 The upper run of the trough conveyor 1 comprises one element of the press by which the liquid is extracted from the material and it is supported on one or more girders 17 which extend the length of the frame. In the 25 present construction I have shown four such girders 17, the upper run of the trough conveyor being supported on the top of said girders.

30 In order to reduce friction between the conveyor and the supporting girders I propose to interpose a plurality of roller chains 18 between these elements. There is one such roller chain for each girder and preferably 35 each girder will carry at its upper edge a track member 19 of steel, or other wear-resisting material, on which the roller chains travel. These roller chains pass around guides 20 and are idle elements in that they 40 are not positively driven. They function in the same way as roller bearings and serve not only to reduce friction but also to reduce the wear.

45 As stated above, an endless chain feed unit is employed to aid in feeding the material to be dried into the conveyor and this feed unit also functions as a press to initially press the material and give it the ribbon-like shape. Such feed unit is indicated generally at 21 and 50 it comprises a plurality of slats or platens 22 connected together to form an endless chain arrangement which passes around sprockets or wheels 23 that are supported in a suitable frame 24. One end of this feed press operates 55 in a suitable hopper 25 into which the material 95 to be dried may be delivered. This feed unit is positively driven and it co-operates with the trough conveyor to feed material to the latter and also to initially compress 60 said material. The feed unit is arranged so that it has an angular relation to the conveyor, the entering end of said unit being spaced from the conveyor further than the delivery end so that as the material passes between the conveyor and the feed press it is ini-

tially compressed and a part of the liquid therein is expressed therefrom.

After the material has been delivered from the feed unit it is carried by the trough conveyor to the main press 26 which is also an endless chain device that has a slight angular relation to the conveyor, and co-operates therewith to subject the material to a progressively-increasing pressure as it is carried along on the conveyor, thus forcing the liquid 75 therefrom.

The feed unit 21 is preferably in the nature of a floating element although it is positively driven. The delivery end thereof is shown as connected to the main press 26 through a link 27, this link arrangement maintaining the delivery end of the feed press in proper position while permitting said feed press to rise and fall more or less. The receiving end of the feed press is supported by cables or 85 flexible connections 28 which extend over pulleys 29 on the frame 4 and lead to the winches 30. With this arrangement the left-hand end of the feed press may be raised or lowered and the speed at which the material 90 is fed into the device may thus be controlled.

95 The feed unit is positively driven and while any appropriate mechanism for driving it may be employed I have herein illustrated it as being connected to and driven from the shaft 9. This shaft 9 is connected by a suitable driving gear 47 to a shaft 48 which is connected by a variable speed drive 84 to the shaft 49, the latter being connected by a sprocket chain 50 to the shaft 86 that is journalled in blocks 91 slidably mounted in ways 39 formed in the post 38 of the frame. This shaft 86 is connected by a suitable sprocket chain with a sprocket gear 52 that is fast on the shaft of the sprocket 23 of the feed unit. This variable speed drive 84 provides for varying the speed of operation of the feed unit relative to the conveyor.

100 The main press 26 is formed of a plurality of slats or platens 31 linked together to form an endless chain arrangement which passes around sprocket wheels 32, 33. These sprocket wheels are carried at the ends of a frame comprising a plurality of connected 115 girders 34. The sprocket wheels 32, 33 are fast on shafts 70, 86 which are journalled in the girders, the shaft 86 also finding a bearing in the blocks 91. The length of the platens 31 is such as to permit them to enter between the sides 6 of the trough, as shown in Fig. 3. I have herein shown roller chains 35 interposed between the lower run of the main press 26 and the under side of the girders 34, these roller chains serving to reduce friction and also to resist wear. The frame comprising the girders 34 on which the main press is mounted is preferably adjustable, thus making it possible to vary the angular relation between it and the conveyor 120 and consequently the amount of compression 125 130

given to the material as it passes along the converging space between the conveyer and pressing element. At the entering end of the main press this adjustment is secured by adjusting screws 36 which are screw threaded into the supports 37 formed on the frame 4 and on which the blocks 91 rest. By adjusting the screws 36 the entering end of the main press may be raised or lowered and thus its angular relation to the trough conveyer can be varied.

The right hand or delivery end of the main press has associated therewith a hydraulic jack which functions both to determine the degree of pressure to which the material is subjected and also to control automatically the thickness of the sheet or ribbon of material at the delivery end. This hydraulic jack device consists of a jack casing 40 on each side of the machine, each casing having a plunger 41 therein which is rigidly secured to cross girders 87 that extend transversely of the girders 17. Each jack casing is connected by tie rods 42 to a yoke device 43 which rests on a roll or bearing 45 that is supported on a bearing block 44 secured to cross girders 88 which extend transversely of the girders 34 on the upper side thereof. The two hydraulic jacks thus act on opposite ends of the cross girders 88.

When water under pressure is introduced into the jacks, they will be extended and will thus draw the delivery end of the main press toward the conveyer. The desired pressure in the jacks is maintained by a suitable pump device 78 comprising a plurality of pump cylinders, the pistons of which are connected to a crank shaft 79 that may be driven from any suitable source of power, said shaft being shown as having a belt pulley 77 fast thereon. This pump device is provided with a delivery pipe 76 through which pumped water under pressure is pumped into the cylinders 40.

The pressure which is maintained in the cylinders 40 will, of course, determine the pressure to which the material is subjected at the delivery end of the conveyer. If desired, a suitable relief valve 75 may be employed as a means of limiting the pressure in the jacks.

The pump 78 which I employ is preferably so constructed and connected to the hydraulic jacks that when they have been extended to a predetermined point thereby reducing the ribbon 74 of material to a predetermined thickness, said pump will be rendered inoperative. This may be herein provided for by connecting the tie rods 42 of one of the jacks to a controlling lever 73 pivoted to the frame at 72, said lever having a connection 71 leading therefrom to the suction valves of the pump, the construction being such that when the controlling lever 73 is moved downwardly to a predetermined point by the extending

movement of the jacks the suction valves of the pump will be open so that the pump will run idle.

I have also provided a stop device to positively limit the movement of the delivery end of the press toward the trough conveyer. This stop device comprises arms or abutments 93 secured to the girders 17 and stop members 92 secured to the girders 34, said stop members limiting the movement of the delivery end of the press toward the trough conveyer and thus preventing the slats of the press from engaging the slats of the conveyer.

The main press is shown as being positively driven and for this purpose the sprocket 33 is fast on the shaft 86 which, it will be remembered, is driven from the motor shaft 9. The variable speed driving device 84 provides for varying the speed of the main press relative to that of the conveyer, if desired.

In the operation of the device the material to be dried is deposited in the hopper and is properly distributed on the trough conveyer by the feed press 22. This feed unit functions not only to assist in feeding the material to the trough conveyer but also to initially compress the material and press part of the liquid out of it. Furthermore this feed unit serves to form the material into a ribbon or sheet which is carried along by the conveyer. As this ribbon or sheet passes beneath the main press 26 and is carried along the converging space between the upper run of the trough conveyer and the under run of the main press said ribbon or sheet is subjected to a progressively-increasing pressure which may be of such an amount at the delivery end as to force out of the material the desired proportion of liquid so that the material may be brought to any desired degree of dryness.

One element contributing to the efficiency of the drier is a constructional feature by means of which the liquid which is forced out of the material will be drained off as fast as it is freed of the material thus obviating the possibility of any of the expressed liquid finding its way back into the dry material again.

It will be noted that the girders 17 are arranged at an inclination with the delivery end of the trough conveyer at a higher elevation than the feeding end. As a result of this all the liquid which is expressed from the material tends to flow away from the delivery end and as the material is moving toward the delivery end said material keeps moving away from the water which is squeezed out of it.

I will preferably make the trough conveyer so that the slats 5 are spaced slightly from each other and may also undercut the edges of the slats. The slight space between the slats furnish drain openings through which the expressed liquid will readily drain away and this draining is facilitated by the undercut edges 68 of the slats.

Having thus described the invention what is claimed as new and desired to be secured by Letters Patent, is:

1. In a mechanical drier, the combination with an endless trough conveyer having a straight upper run, of an endless floating feed element for feeding material to be dried to the conveyer and for subjecting it to initial compression, and an endless belt compressing element having its lower run co-operating with the upper run of the conveyer to act on the initially-compressed material as it is carried on said upper run of the conveyer and subject it to further compression, said lower run of the compressing element having an angular relation to the upper run of the conveyer whereby the material is subjected to a progressively-increasing pressure.
2. In a mechanical drier, the combination with an endless trough conveyer having a straight upper run, of an endless feed element for feeding material to be dried to the conveyer and for subjecting it to initial compression, said feed element being pivoted at one end on a floating pivot, an endless belt compressing element having its lower run co-operating with the upper run of the conveyer to act on the initially-compressed material as it is carried on said upper run of the conveyer and subject it to further compression, said lower run of the compressing element having an angular relation to the upper run of the conveyer whereby the material is subjected to a progressively-increasing pressure, and means for adjusting said angular relation.
3. In a mechanical drier, the combination with an endless conveyer having a straight upper run, of a floating feed element having an endless feed member for feeding material to said conveyer, both ends of said feed element being vertically movable relative to the conveyer and said feed element having an angular relation to the upper run of the conveyer and operating to initially compress the material, means to adjust said angular relation, and an endless belt compressing element co-operating with said conveyer to act on the initially-compressed material and subject it to a progressively-increasing pressure as it is carried along on the conveyer.
4. In a mechanical drier, the combination with an endless conveyer in the shape of a trough, of an endless feed element for feeding the material to be dried to said conveyer and for initially compressing said material, means for manually adjusting the angular relation of said feed element to said conveyer thereby to vary the rate of feed, and an endless belt compressing element co-operating with the conveyer to act on the initially compressed material and further compress it thereby to express liquid therefrom.
5. In a mechanical drier, the combination with an endless trough conveyer, of means to support the upper run thereof, an endless

feed element for feeding the material to be dried to said conveyer, an endless belt compressing element co-operating with said conveyer to subject the material thereon to a progressively-increasing pressure as it is carried along on the conveyer, means for adjusting the angular relation between the compressing element and a conveyer, a link connecting one end of the feed element with the adjustable end of the compressing element, and adjustable means for supporting the other end of said feed element.

6. In a mechanical drier, the combination with an endless trough conveyer, of an endless feed element both ends of which are capable of vertical movement co-operating with the receiving end of said conveyer to regulate delivery of material to be pressed thereto and to initially compress said material, and an endless belt compressing element also co-operating with said conveyer to act on the initially compressed material and subject it to a progressively-increasing pressure as it is carried along on the conveyer.

In testimony whereof, I have signed my name to this specification.
